UNITED STATES PATENT OFFICE.

FELIX NIEMEIER, OF BROMBERG, GERMANY.

INLET BOX OR GULLY FOR DRAIN-PIPES OR THE LIKE.

No. 894,339.

Specification of Letters Patent.

Patented July 28, 1908.

Application filed October 28, 1907. Serial No. 399,619.

To all whom it may concern:

Be it known that I, FELIX NIEMEIER, government architect, subject of the German Emperor, residing at 21 Moltkestrasse, Bromberg, in the Kingdom of Prussia, German Empire, have invented certain new and useful Improvements in Inlet-Boxes or Gullies for Drain-Pipes or the Like, of which the following is a full, clear, and exact description.

10 This invention relates to an improved inlet box for tubular conduits which are employed to form a continuation of open water channels.

It is designed chiefly for use in agricultural improvement works where in regulating minor water channels and in the irrigation and drainage of meadowland and marshes, and especially in drainage installations, underground pipes are frequently substituted for 20 open ditches, as this obviates obstacles in the cultivation of the soil and involves very little expense for maintenance. Such a pipe channel requires to be secured with great care against obstruction by materials carried into the pipe, and the inlet box forming the subject of the present invention is intended to serve this end. Such water inlets may also be employed in the drainage of railway works and road embankments.

30 The drawing illustrates the invention in which:

Figure 1 is a front elevation with one half of the grating omitted. Fig. 2 shows a longitudinal section, Fig. 3 shows a half plan 35 and half horizontal section.

The inlet box is made of cement concrete with wire insertions. On the front side it is semicircular in plan, in order to insure over the largest possible section a flow of water 40 directed towards the center of the pipe conduit, from the ditch or reservoir *a* which drains into the conduit. At the top the box is partly closed by means of a roof or cover, the opening remaining is intended to let in the 45 water when the water level is very high. To

prevent weeds and other objects carried away by the water, from entering into the box the upper orifice is covered with an iron grating *c*.

Slots *d* are arranged in the front face, through which the water is intended to enter 50 when at a medium or low level. The lower margin of the slots is situated on a level with the base of the pipe conduit to be protected by the inlet box, so that the water can be drained off down to the level of the bottom of 55 the conduit and no loss of head will thus arise through the interposition of the box. The bottom *e* of the box is recessed in the form of a mud trap, so that any sand and mud may be deposited there. To facilitate the per- 60 odical removal of these deposits the grating *c* on the top of the box can be turned back on hinges *f* on the upper side of the box. In the back of the box there is an orifice correspond- 65 ing to the pipe conduit *b* to be inserted there.

What I claim and desire to secure by Letters Patent is:—

1. An inlet box for pipe conduits having a semicircular front face provided with a plurality of inlet openings and an outlet opening 70 arranged in its rear face opposite said curved front face.

2. An inlet box for pipe conduits having a semicircular front face provided with a plurality of vertically spaced series of openings, 75 and an outlet opening arranged in its rear face opposite said curved front face.

3. An inlet box for pipe conduits having a semicircular front face provided with a plurality of inlet openings, an outlet opening 80 arranged in its rear face opposite said curved front face, a mud trap formed in said box below said outlet and inlet openings and a removable cover to permit access to said trap.

In witness whereof, I subscribe signature, 85 in presence of two witnesses.

FELIX NIEMEIER.
